UNITED STATES PATENT OFFICE.

STURGES WHITLOCK, OF SHELTON, ASSIGNOR TO THE WHITLOCK MACHINE COMPANY, OF BIRMINGHAM, CONNECTICUT.

PRINTING-PRESS.

SPECIFICATION forming part of Letters Patent No. 544,075, dated August 6, 1895.

Application filed January 5, 1894. Serial No. 495,782. (No model.)

To all whom it may concern:

Be it known that I, STURGES WHITLOCK, of Shelton, in the county of Fairfield and State of Connecticut, have invented a new Improvement in Printing-Presses; and I do hereby declare the following, when taken in connection with accompanying drawings and the letters of reference marked thereon, to be a full, clear, and exact description of the same, and which said drawings constitute part of this specification, and represent, in—

Figure 1, a plan view of a printing-press constructed in accordance with my invention; Fig. 1^a, a sectional detail view on the line *a b* of Fig. 1, looking toward the cam *j'* and designed to show the same and its co-operating parts; Fig. 1^b, a sectional view on the line *c d* of Fig. 1, looking inward, showing one of the arms by means of which the rock-shaft *J'* is carried from the transfer-shaft *I'*; Fig. 2, a view thereof in vertical central longitudinal section; Fig. 2^a, a similar view showing the flier in the position which it occupies when taking a sheet from the transfer fingers and grippers; Fig. 3, a view of the press in side elevation from what I have termed its "outer" side; Fig. 3^a, a view showing the connection between the link *G'* and the shaft *G²* of the mechanism for raising and lowering the impression-cylinder; Fig. 4, a detached broken view in side elevation, showing the feeding, transferring, and slitting instrumentalities of the press on a larger scale than in Fig. 3; Fig. 5, a detached broken view partly in elevation and partly in section, showing the rocker-arm of the fly and the means for operating the lower fly-gripper shaft; Fig. 6, a detached view in side elevation of one of the feed-gages drawn to full size; Fig. 7, a view thereof in rear elevation; Fig. 8, a broken view in elevation of the circular knife and the circular slitter or die with which the same co-operates; Fig. 9, a detached view in side elevation of one of the intermediate arms *J^{2a}* and the hub and transfer-finger *I* formed integral therewith; Fig. 10, a plan view of the same part.

My invention relates to an improvement in front-delivery printing-presses of the type in which the sheets are delivered with their last-printed sides uppermost, the object being to produce a simple, compact, convenient, and

durable machine, operating without tremor, and adapted to feed the sheets without wrinkling or defacing their edges, to transfer them after printing without smutting them, and to uniformly deliver them with their last-printed sides uppermost.

With these ends in view my invention consists in a machine having certain details of construction and combinations of parts, as will be hereinafter described, and pointed out in the claims.

In the following description I shall set forth the construction of various instrumentalities of my improved machine in the order in which they operate.

The feed-table *A*, which is of ordinary construction and location, is furnished upon its upper face with a feed-plate *A'*, extending beyond its inner edge. Two feed-gage brackets *A² A³*, secured to the opposite ends of the table, overhang its inner edge and carry at a higher plane than the same an oscillating feed-gage shaft having its ends journaled in them and constructed with a longitudinal groove *B'*, as clearly shown in Fig. 6. Two feed-gages, each consisting of a horizontal sleeve *C* and an arm *C'* depending therefrom, are mounted upon the said feed-gage shaft, to which they are secured in any desired position of adjustment by means of screws *C² C³* mounted in their respective sleeves and entering the longitudinal groove *B'* in the said shaft. The lower end of the arm *C'* of each feed-gage is constructed with a foot *C³*, the convex lower face of which is recessed to receive the forward end of a longitudinally-bowed steel tongue *C⁴*, which is secured to the foot by means of a screw *c*. The convex lower face of the foot *C³* and the bowed tongue *C⁴* are both formed on the same circle, which is concentric with the shaft *B*. Each feed-gage is also provided with an adjustable plate *C⁵* located upon the front face of its arm *C'* and coextensive therewith, the upper end of the plate being rounded and inserted into a socket *c'* formed between the sleeve *C* and the arm *C'* of the gage, while its extreme lower end is slightly cut away, as at *c²*, to fit over the bowed tongue *C⁴*. The said plate is held in any desired position of adjustment by means of a thumb-screw *C⁶* passing through a smooth

transverse opening or bore c^3 formed in the arm C' and taking into a threaded opening c^4 formed in the plate C^5 , and by a thumb-screw C^7 mounted in the plate C^5 and impinging at 5 its inner end against the inner face of the arm C' . As thus arranged it will be seen that the screws C^6 C^7 will act in opposition to each other in adjusting the plate C and fixing it in place when rightly adjusted. The lower end 10 of the plate C^5 is formed with a beveled fin-like deflector C^8 , standing at a right angle to its plane and guiding the inner edges of the sheets into place against the extreme lower end of the plate, in case they are presented 15 with their inner edges upturned or too high.

It will be understood that in being fed the sheets to be printed are butted at their lower edges against the lower ends of the plates C^5 C^5 of the two feed-gages, and therefore that 20 the adjustment of the said plates C^5 C^5 regulates the right feeding of the sheets, so far as their projection over the inner edge of the table is concerned. In setting the press the plates may be adjusted alike or differentially, 25 as circumstances may dictate. If, for instance, the press is in any way out of truth, the variation may be compensated for by a different adjustment of the plates of the two feed-gages.

30 It will be understood, of course, that the gages are adjusted toward and away from each other on the rock-shaft B according to the length of the sheets to be printed, and that if desired more than two gages may be used.

35 The tongues of the gages support the inner edges of the sheets in their projection beyond the inner edge of the feed-table. The feed-gages therefore not only gage the feeding of the sheets, but also support the inner edges

40 thereof in their projection over the inner edge of the feed-table, and they fulfill both of these functions without crumpling or wrinkling or in any way distorting or defacing the edges of the sheets, all to obvious advantage, not 45 only with respect to the sheets themselves, but also to the operation of the press, which is constructed to work so closely that it demands the right presentation of the sheets to it, for otherwise it will not "register" them.

50 The feed-gage shaft B is rocked or oscillated by means of an arm B^x , secured to its right or feeder end. Here, I may say, that the side of the press on which the feeder stands is called the "right" or "feeder" side and the 55 opposite side the "left" or "off" side. These terms I shall employ hereinafter in the sense above indicated to assist in describing my improvement. The said arm B^x carries an antifriction-roller B^2 , which rides upon a cam

60 B^3 , mounted upon a sleeve or hub B^4 , encircling a stud D , projecting outward in a horizontal plane from the right side of the frame D' of the press, the said sleeve or hub being driven by means of a driven pinion D^2 , also

65 mounted upon the sleeve or hub aforesaid and meshing into a driving-pinion D^3 , secured to the feeder-side end of the shaft E of the

impression-cylinder E' , which is of ordinary construction and operation.

Between the two feed-gages already described are located two drop-fingers F F , which extend rearward and inward over the inner edge of the feed-plate A' , with which they co-operate, the said fingers being located in substantially a horizontal plane. They are 75 mounted upon an oscillating or rocking drop-finger shaft F' , to which they are adjustably secured by means of set-screws F^2 F^2 mounted in them, as well shown in Fig. 2. The said shaft F' is journaled at its ends in arms G G , 80 located upon the upper faces of and extending forward from the boxes G' , in which the cylinder-shaft E is mounted. The feeder-side end of the said shaft F' is provided with a handle F^3 for its manual operation and with 85 an operating-arm F^4 for its automatic operation, the latter riding upon a cam F^5 , secured to the extreme inner end of the hub or sleeve B^4 , to which the feed-guide cam B^3 and the driven pinion D^2 are also attached, as afore- 90 said.

The press is timed so that when the sheets are fed the drop-fingers will be lifted above the surface of the feed-plate A' for a sufficient distance to allow the inner edges of the sheets 95 to pass freely under them for engagement with and location by the feed-gages. Then after a sheet has been rightly placed the drop-fingers are allowed to drop and engage with it, so as to prevent its displacement when the 100 feed-gages are swung forward and away from it and when it is being grasped by the cylinder-grippers H , which will be referred to more at length later on.

The feed-gages and drop-fingers together 105 constitute the registering and gaging instrumentalities of the press. They are not, however, necessarily used in conjunction, for the drop-fingers might be dispensed with or replaced by something else, and I would have 110 it understood that I do not limit myself to their use, nor to constructing and operating them in the particular manner shown and described, for they are not broadly new with me, and I claim them only in combination. 115

The impression-cylinder E' has already been said to be of ordinary construction and operation, and is vertically reciprocated within narrow limits in the manner well known in this class of presses. As herein shown, each of the boxes G' of the shaft E is connected to the upper ends of two vertical guide-rods G^2 G^2 , attached at their lower ends to a vertically-movable head G^3 , mounted in the frame D' of the press. Each of the sliding heads G^3 is positively operated for being depressed by means of two toggle-levers G^4 and G^5 , the former being pivotally attached to the head and the latter being attached to a stud G^6 mounted in the press-frame D' . Each of the toggle-levers G^4 is connected at its lower end to an operating-link G^7 , which is constructed at its inner end with an elongated slot G^7a , through which the shaft G^8 passes, and provided near

the ends of the said slot with antifriction-rollers G^7 , which are acted upon by a cam G^7 mounted on the said shaft, as shown in Fig. 3^a. A heavy spiral spring G^9 , located under each of the boxes, exerts a constant effort to raise the same, and hence lift the cylinder into its elevated position. It will be understood that when the levers G^5 and the upper ends of the levers G^4 are brought into line the boxes, and hence the impression-cylinder, will be positively drawn downward, and that it will be released for being lifted back again by the spiral springs G^9 G^9 , when the said levers G^5 and the upper ends of the levers G^4 are thrown out of line, as shown in Fig. 3. I would have it understood, however, that I do not limit myself to the particular means shown for raising and lowering the impression-cylinder.

The left or off side end of the shaft G^8 carries a gear-wheel G^{10} , which meshes into a pinion G^{11} carried by the corresponding end of the main driving-shaft G^{12} of the press, the said end of the shaft G^{12} also carrying a gear-wheel G^{13} , meshing into an intermediate idle gear-wheel G^{14} , journaled on a stud mounted in the off side of the press-frame and meshing into a gear-wheel G^{15} secured to the corresponding end of the cylinder-shaft E , as shown in Fig. 1.

The grippers H , before mentioned, project outward through a longitudinal opening H' formed in the impression-cylinder, within which they are mounted on a shaft H^2 , which is rocked or oscillated to open and close the grippers, which take the sheets from the feed-table and deliver the same after they are printed to the transfer devices of the press. The mechanism for rocking the gripper-shaft H^2 is old and not fully shown, but it includes a reciprocating pin H^3 , which operates the shaft in opening the grippers, and a corresponding reciprocating pin H^4 , which operates the shaft in closing the grippers, the said pins being operated alternately by a rocker H^5 swinging on a pin H^6 and actuated by a grooved cam H^7 , with which it is connected by means of a pin H^8 , the cam H^7 being also located upon the sleeve or hub B^4 before mentioned. I do not, however, limit myself to the devices shown for opening and closing the cylinder-grippers, as any suitable devices may be used for that purpose.

The transfer devices of my improved press are located horizontally, or substantially horizontally, in front of the registering devices and mounted in the arms G G , which, as before described, are secured to the upper faces of the boxes G' G' and extend forward therefrom. The transfer devices, therefore, partly take of the vertical movements of the impression-cylinder. The said devices comprise a series of transfer-fingers I secured to a shaft I' , the ends of which are mounted in the ends of the said arms G G , this shaft constituting the main shaft of the transfer devices, and being provided at its left or off side end with a gear-wheel I^2 meshing into the gear G^{15} on

the same end of the cylinder-shaft E , as shown by Fig. 1. With the transfer-fingers I combine a series of transfer-grippers J, which are mounted upon a rock-shaft J' , the ends whereof are journaled in arms J^2 J^3 rigidly attached to the main shaft I' , with which the shaft J' is thus caused to rotate. The rock-shaft J is supported between its ends in hub-like bearings or sleeves formed at the outer ends of four intermediate arms J^{2a} , located at about equal distances apart. The inner end of each of the said arms J^{2a} terminates in a large hub, through which the said transfer-shaft passes. Each of the said hubs has one of the transfer-fingers I formed integral with it, the said fingers being thus secured to the said shaft. By preference, and as herein shown, each of the arms J^{2a} has the hub-like bearing-sleeve at its outer end, the large hub at its inner end and the transfer-finger I upon the latter formed in one piece. In Figs. 9 and 10 of the drawings I have shown detached views, in side elevation and in plan, of the combined part just above described. In the operation of the transfer devices the grippers thereof are intermittently moved away from the transfer-fingers and closed over the same. As herein shown, the grippers are kept normally closed by means of the expanding tension of a spiral spring J^4 encircling a rod J^5 , attached at one end to the arm J^6 of a head J^7 , carried by the gripper-shaft J' , and passing at its other end through a finger J^8 formed integral with the arm J^8 , before mentioned. The said spring is interposed between the arm J^6 and the finger J^8 , and exerts a constant effort to elongate itself, and hence to throw the arm J^6 forward and to rock the gripper-shaft J' , which is positively rocked in the other direction, for moving the grippers away from the fingers by means of an arm J^9 , also formed integral with the head J^7 , and carrying an antifriction-roll J^{10} , which engages as the shaft J' revolves around the shaft I' with cam-faces j j formed at the upper end of a yoke-shape cam j' , which is centrally cut away at its upper end to fit over the shaft I' , which forms a support and guide for it. The said cam j' is rigidly attached at its lower end to the inner end of a horizontal reciprocating pin j^2 , the outer end of which is connected with the rocker H^5 , which reciprocates it. Under this construction the said transfer-gripper cam j' is moved inward into position to be engaged by the antifriction-roll J^{10} , and thus operate the transfer grippers once in four revolutions of the transfer-shaft I' , and once in two revolutions of the cylinder-shaft E . I would have it understood, however, that I do not limit myself to the means illustrated and described for operating the transfer devices, and particularly for operating the transfer-grippers.

The slitting devices of my improved press consist of a circular die or slitter K and a circular knife K', the latter being constructed to enter a circumferential groove formed in the former, as clearly shown in Fig. 8 of the

drawings. The said die is made in two corresponding semicircular parts adapted to be bolted together, being so made in order to adapt it to be applied to and removed from the transfer-shaft I' at pleasure. The knife K' is mounted in the forked upper end of a plunger K^2 , the lower end of which plays in a socket K^3 , formed in a socket-piece K^4 mounted on a shaft k , supported by two brackets K^5 bolted to the frame D' of the press, as clearly shown in Fig. 4 of the drawings. A spiral spring K^6 , interposed between the bottom of the socket K^3 and the lower end of the plunger K^2 , exerts a constant effort to lift the plunger and press the knife against the periphery of the circular die or slitter, whereby the knife is caused to follow the slitter as the same moves up and down with the impression-cylinder and the instrumentalities connected therewith. The knife is rotated by frictional contact with the slitter, which is positively rotated with the shaft I . If desired the positions of the knife and slitter may be reversed, but the construction shown is preferable.

The printed and slitted sheets are taken from the transfer devices and neatly piled upon the delivery-table L by means of a fly, which comprises two short fly-arms M , movably fulcrumed, so to speak, at their lower ends to the frame D' of the press. To that end they are, as shown, constructed at their lower ends with toothed segments M' , which mesh into horizontal racks M^2 supported upon beds M^3 bolted to the frame of the press. A horizontal tie M^4 , consisting of a shaft, extends between the two arms and binds them together, the ends of the said tie being provided with antifriction-rollers m , which play back and forth in horizontal slots M^5 formed in brackets M^6 secured to the press-frame, whereby the tie assists in holding the fly in place. A gripper-shaft N , journaled in the outer ends of the fly-arms so as to rock or oscillate therein, carries the upper fly-grippers N' , which are arranged in a horizontal series. Two arms N^2 N^2 , rigidly secured to the said shaft N and extending rearward therefrom, have the lower gripper-shaft O journaled in their outer ends, so as to rock or oscillate therein, the lower gripper-shaft carrying a corresponding series of grippers O' , which co-operate with the grippers N' , before mentioned. Hereinafter the grippers N' will be spoken of as the "upper fly-grippers," and the grippers O' as the "lower fly-grippers."

To maintain the upper and lower fly-grippers N' and O' in substantially horizontal positions during the movements of the fly, the same is provided with a rocker-arm P , which, as herein shown, is formed integral with the inner of the two arms N^2 N^2 , which connect the lower gripper-shaft O with the upper gripper-shaft N . The said rock-arm P extends forward and is connected at its outer end with the upper end of a long bowed rocker-rod P' , the lower end of which is pivotally connected

with the left or off side of the frame of the machine by a stud P^2 , located a considerable distance below the lower ends of the fly-arms. Under this construction the rocker-rod swings in the arc of a larger circle than the fly-arms, and through the medium of the rocker-arm rocks the upper and lower gripper-shafts, so that the grippers mounted upon them will move back and forth in substantially horizontal positions.

The lower fly-grippers are opened and closed, with respect to the upper fly-grippers, by means of operating devices acting independently of the upper fly-grippers and the upper gripper-shaft N . These devices consist, as shown, of an operating-head Q , rigidly secured to the lower gripper-shaft O and depending therefrom, and constructed with a lever-arm Q' and a bearing-arm Q^2 , which carries a long plunger Q^3 , the outer end of which plays back and forth through a sleeve Q^4 , formed at the outer end of a post mounted in the outer end of the rocker-arm P . The outer end of the lever-arm Q' is attached to a long link or rod R , pivotally connected with the upper end of an operating-lever R' , hung upon a stud R^2 to the left side fly-arm M , the lower end of this lever being provided with an antifriction-roll R^3 , which engages as the fly approaches the opposite ends of its stroke with beveled opening-toes R^4 and R^5 located diagonally opposite each other in different horizontal planes, rigidly mounted in the press-frame, and separated by a distance approximately corresponding to the horizontal movement of the fly. In Fig. 2 of the drawings the antifriction-roll R^3 is shown in engagement with the opening-toe R^4 . When, however, the fly is at the end of its instroke, the lever R' will be so far reversed in position that the roll R^3 will engage with the opening-toe R^5 .

The lower grippers are closed after being opened by the mechanisms just described, and normally maintained in closed positions by the effort to elongate of a spiral spring q , interposed between the sleeve Q^4 and the bearing-arm Q^2 . By pushing against the former as a point of purchase it operates to swing the operating-head Q inward, thus rocking the lower gripper-shaft O outward and lifting the lower grippers O' upward against the lower faces of the upper grippers N' .

The fly is operated back and forth, as herein shown, by means of a short link S , connected at its inner end with the right or feeder side end of the tie M^4 , and at its opposite end with the upper end of a long fly-lever S' , fulcrumed about midway of its length to the same side of the press-frame D' , and pivotally connected at its lower end with the outer end of a link S^2 , the opposite end of which is pivotally connected with a crank S^3 , which is mounted upon and rotated by the shaft G^8 of the press, the link S^2 being but slightly longer than the crank S^3 . Under the construction just described, the fly is caused to move com-

paratively slowly on its outward stroke, and very slow as it approaches the end thereof, so that the printed sheets are delivered with little momentum and fall quietly to their places on the pile. The particular arrangement of links and lever may be replaced by some other device operating in substantially the same way.

It may be well to state here that the grippers of the fly are opened before they reach the paper, which is delivered to them by the transfer grippers and fingers. Then, in the operation of the machine, the fly-grippers advance over the edge of the paper, which mean-
15 while is being moved between them by means of the transfer grippers and fingers. Now when the fly begins its outstroke the grippers thereof will close at the same point that they opened, but upon the paper which, as stated, has been moved between them meanwhile by the action of the transfer grippers and fin-
20 gers.

The printed sheets are piled by the action of the fly upon the delivery-table L, the upper surface of which has shallow grooves l formed in it, and intersecting each other at a right angle and adapted to receive the lower ends of movable upright guides T, which are thus supported in vertical positions. By
30 preference one or more of the guides will have a vertically-arranged star-shaped guide-wheel T' mounted in its upper end. These guides are shifted about upon the upper surface of the said table according to the size of the
35 sheets being printed. It will be understood that the sheets will trail over the guides, with which, however, they have such superficial contact that they will be neither retarded nor in any wise defaced.

40 I am not obliged, of course, to groove the delivery-table as described, nor to provide it with movable guides, nor am I limited to using that construction in connection with the other instrumentalities of the press, for it is applicable to other presses as well.

45 I wish to call attention to the fact that in my improved press the fly takes the sheet from the transfer devices at a point close to and below the top of the impression-cylinder and at a time when the transfer devices, and hence the sheet, are moving at a speed sub-
50 stantially the same as that of the fly. By reference to Fig. 1 of the drawings it will be seen that the impression-cylinder E and transfer-
55 shaft l' are geared directly together by means of the gears G¹⁵ and I², so as to run at the same rate of speed to which the speed at which the flier is oscillated is timed by forming the crank S³ and its several connections of suit-
60 able length. The fly therefore takes the sheets gently and without suddenly intercepting their movement in another direction. Furthermore it will be observed by reference to Fig. 3 of the drawings that the delivery-
65 table is extended inward to a point compara-
tively close to the impression-cylinder, where-
by the movement of the flier is reduced to

the minimum and economy of time secured, whereas in machines in which the delivery-table is located at a point remote from the impression-cylinder the flier has to be moved for a long distance and very rapidly, in order not to lose time. Of course the more rapidly the machine is operated the more the difficulty of handling the paper and the greater the
70 wear of the machine.

75 The forward end of the delivery-table is provided with a jogger U, provided with a series of upright pins U', and having sliding connection with the lower face of the delivery-table, the jogger being thereto provided with a horizontal arm U², which is shown in Fig. 2 of the drawings, the said arm passing through two horizontal bearings U³ U³ depending from the table, as shown in the same figure. A
80 spring U⁴ connecting the inner end of the said arm with the lower face of the table, provides for the inward movement of the jogger after the same has been moved outward by the en-
gagement of a long arm U⁵ depending from
85 it by the tie E⁴. As the fly approaches the end of the outward stroke the said tie en-
gages with the depending arm U⁵ of the jog-
ger, whereby the jogger is moved outward to
clear the sheet carried by the fly. Then as
90 the fly begins to move inward again the spring
U⁴ of the jogger draws it inward, and the
jogger squares the sheet last delivered upon
the pile.

95 The inner end of the delivery-table is fur-
nished with a hinged flap L', which may be raised into a vertical position, as shown by dotted lines in Fig. 2, for the convenient in-
sertion and removal of the inking-rollers V.

100 The operation of the different instrumen-
talities of the press has been so fully described in connection with the description of their construction that it is thought unnecessary to give any additional statement of the operation of the press.

105 110 It has been suggested in connection with the description that the different instrumen-
talities are not necessarily used in the combi-
nations herein shown, and that the particular operating mechanisms may be varied. I would
115 therefore have it understood that I do not limit myself to the exact construction shown and described, but hold myself at liberty to make such changes and alterations as fairly fall within the spirit and scope of my inven-
120 tion.

125 I am aware that it is old to hold a circular knife employed for cutting paper up in position to do its work by means of a spring. I am further aware that it is old to construct a printing-press with a circular die and a circular slitter entering the same. I am also aware that it is old to employ a segment and rack for the operation of the flier of a print-
130 ing-press. I am further aware that it is old to operate a reciprocating jogger by means of the flier of a printing-press. I do not, therefore, claim any of those constructions broadly.

Having fully described my invention, what

I claim as new, and desire to secure by Letters Patent, is—

1. In a printing-press, the combination with the registering devices thereof, of an impression cylinder, transfer devices located horizontally or substantially horizontally in front of the said registering devices, a flier constructed and arranged to take the sheets when it is in motion, from the transfer devices, at a point located close to the impression cylinder and below the top thereof, and a delivery table to receive the sheets when they are released by the flier, substantially as described, and whereby the sheets are fed with their printed sides uppermost and without face contact, by the transfer devices to the flier when the latter is in motion.
2. In a printing-press, the combination with the registering devices thereof, of an impression cylinder, transfer devices located horizontally or substantially horizontally in front of the registering devices, and including a transfer shaft, transfer fingers, transfer grippers, and means for rotating the said fingers and grippers, and also means for operating the grippers to move them toward and away from the fingers; a flier provided with grippers for taking the sheets, when it is in motion, from the transfer devices at a point located close to the impression cylinders and below the top thereof, means for operating the grippers of the flier, and a delivery table, substantially as described, and whereby the sheets are fed, with their printed sides uppermost and without face contact, by the transfer devices into the grippers of the flier when the latter is in motion.
3. In a printing press, the combination with the registering devices thereof, of an impression cylinder, vertically movable boxes in which the same is mounted, grippers carried by the said cylinder, operating devices for the said grippers, transfer devices connected with the boxes of the said cylinder, so as to partake of the reciprocating movement thereof and including transfer fingers and transfer grippers, a rotary shaft on which the said fingers are mounted, a rock-shaft carried by the said rotary transfer-shaft, revolved thereby and having the transfer grippers mounted upon it; means for rocking the said gripper-shaft and thus operating the grippers, including a reciprocating cam arranged to move horizontally into and out of the path in which an arm mounted on one end of the said rock-shaft revolves; and connections between the said cam and the operating devices of the grippers of the impression cylinder, substantially as described.
4. In a printing-press the combination with an impression cylinder journaled in vertically movable boxes, means for imparting vertical reciprocation to the said boxes and hence to the cylinder, registering devices located above the cylinder, transfer devices connected with the boxes of the cylinder so as to partake of the vertical reciprocations thereof, and lo-

cated horizontally in front or substantially horizontally in front of the registering devices, a circular or disk-shaped slitter or die having a circumferential groove, combined with the transfer devices, and partaking of the movement thereof, a circular knife entering the groove of the die, a plunger in the outer end of which the knife is mounted, a socket-piece containing the said plunger, a spring located in the socket-piece and arranged to act upon the plunger to lift the knife against the die, and a shaft connected with the frame of the press, and carrying the said socket-piece, substantially as described, and whereby the knife is lifted by the spring to follow the slitter when the same is moved upward with the transfer devices and cylinder, and whereby the spring is compressed to permit the knife to be pushed downward by the die when the transfer devices and cylinder make their downward movement.

5. In a printing-press, the combination with the other instrumentalities thereof, of a flier comprising two arms terminating at their lower ends in toothed segments, and a tie connecting the said arms; stationary horizontal racks with which the segments intermesh, operating connections with the flier whereby the said segments are rocked back and forth on the racks, and brackets connected with the frame of the press and containing horizontal slots receiving the ends of the tie to assist in holding the flier in place, substantially as described.

6. In a printing-press, the combination with the other instrumentalities thereof, of a fly comprising two fly-arms movably connected at their lower ends with the press-frame, a tie uniting the said arms, and brackets connected with the press-frame and containing horizontal slots receiving the ends of the tie to assist in holding the fly in place, substantially as described.

7. In a printing-press, the combination with the other instrumentalities thereof, of a fly including fly-arms, an upper gripper-shaft mounted in the upper ends of the said arms so as to rock therein, and carrying a series of grippers, a lower gripper shaft carried by the upper gripper shaft and having a series of grippers mounted upon it, a spring for holding the grippers on the lower shaft normally closed, and means for rocking the lower gripper shaft for opening the lower grippers, comprising a link, means connecting the link and lower gripper shaft, a lever fulcrumed on one of the fly-arms, and two toes located in different planes and substantially at the opposite ends of the instroke and outstroke of the fly, in position to be engaged by the said lever for operating the same, substantially as described.

8. In a printing-press, the combination with the other instrumentalities thereof, of a fly comprising two fly-arms having movable connection at their lower ends with the press-frame, an upper gripper-shaft mounted in the

upper ends of the arms so as to rock therein, a lower gripper-shaft connected with the upper gripper-shaft and arranged to rock in its bearings, a rocker-arm connected with the 5 upper gripper shaft, a rocker-rod connected with the said rocker-arm and also connected with the press-frame at a point below the connection therewith of the fly-arms, and means for operating the lower gripper-shaft 10 independently of the upper gripper-shaft, substantially as described.

9. In a printing press, the combination with the delivery table thereof, of a reciprocating jogger located at the outer end of the said 15 table, constructed with a series of upwardly extending pins, connected with the lower face of the table so as to leave the upper face thereof unobstructed and furnished with a depending operating arm; an oscillating flier 20 comprising two fly arms, and a tie located below the table and uniting the said arms, between which it extends transversely; and a spring for retracting the jogger after the same 25 has been forced outward away from the table by the engagement of the tie of the flier with the depending arm of the jogger, near the end of the outward movement of the flier, substantially as set forth.

10. In a printing-press, the combination 30 with the other instrumentalities thereof, of a fly including two fly-arms having movable connection at their lower ends with the press-frame to which they are in effect movably fulcrumed, a tie connecting the said arms, a link connected with one of the arms, a long 35

fly-lever connected at its upper end with the said link, and fulcrumed to the press-frame, a short link connected with the lower end of the fly-lever, and a driving-crank connected with the said link last mentioned, and shorter than the same, substantially as set forth, and whereby the fly is caused to move comparatively slowly on its outward stroke, and very slow as it approaches the end thereof.

11. In a printing-press, the combination 45 with the other instrumentalities thereof, of a flier comprising two arms terminating at their lower ends in toothed segments, and a tie connecting the said arms; stationary horizontal racks with which the segments intermesh, 50 means for holding the said segments upon the racks as the former rock back and forth upon the latter, a link connected with the flier, a long lever connected at its upper end with the said link, and fulcrumed between its 55 ends to the frame of the press, a short link connected with the lower end of the said lever, and a driving-crank connected with the link last mentioned, and shorter than the same, substantially as described, and whereby the 60 flier is caused to move comparatively slowly on its outward stroke, and very slowly as it nears the end thereof.

In testimony whereof I have signed this specification in the presence of two subscriv- 65 ing witnesses.

STURGES WHITLOCK.
